UNITED STATES PATENT OFFICE.

SEWARD A. HASELTINE, OF SPRINGFIELD, MISSOURI.

PILL AND TABLET COUNTING MACHINE.

No. 817,852.

Specification of Letters Patent.

Patented April 17, 1906.

Application filed April 22, 1905. Serial No. 257,018.

To all whom it may concern:

Be it known that I, SEWARD A. HASELTINE, a citizen of the United States, residing at Springfield, in the county of Greene and State 5 of Missouri, have invented new and useful Improvements in Pill and Tablet Counting Machines, of which the following is a specification.

My invention relates to improvements in a 10 pill and tablet counter, the object of which is to provide a cheap, simple, and durable machine and at the same time one that will quickly and accurately count any desired number of pills or tablets without injuring 15 them and at the same time enable the operator to see that the count is accurate while the count is being made. These objects I attain by means of the device illustrated in the accompanying drawings, forming a part of 20 this specification, in which—

Figure 1 is a view of the entire device, showing a vertical longitudinal section of the hopper and one of the tubes and showing two 25 levers with two contact-points on each and a rubber band on one and a spring on the other, one lever being raised, allowing the tablets to drop out, the other one closed. Fig. 2 is a vertical cross-section of the same. Fig. 3 is 30 a vertical longitudinal section of a modification of the entire device. Fig. 4 is a cross-section of the same. Fig. 5 is a detail cross-section on the line $z-z$ of Fig. 3.

Similar letters indicate corresponding parts in the several figures.

35 A is a hopper or receptacle for the tablets or pills, made any desired shape or size, preferably made long and narrow with flaring ends and the two sides forming an angle coming at the bottom to form a trough just large 40 enough for one of the tablets or pills to roll in the bottom of said trough or hopper on its edge. The tablets are fed into the tubes edgewise, and as they are all the same diameter, although they may vary in thickness, 45 they occupy the same space in the length of the tube.

I provide a stirring mechanism to be operated by the foot of the operator. This may be constructed in different ways, preferably 50 made by means of one or more brushes or arms F to move along in a trough A back and forth as the treadle or stirrup is operated up and down. For this purpose any suitable rubber attachment or a weight at one end for drawing the rod and arms backward may be 55 used. I prefer a spring. As these arms

move back and forth in the trough they drop into the tubes B, which open into the bottom of the trough A. I prefer using a stirrup C and a strap or cord D, which passes over a 60 pulley E. A spring W, attached to the frame A² and to one end O² of the lever O, draws it back, spring W being strong enough to hold the lever O back when not pressed by the foot in the stirrup C. The upper end of the 65 lever O is connected with a rod P. Said rod P passes through the trough A longitudinally, and to it I attach arms F. Said arms may be any desired number and are preferably covered with rubber tubes to prevent injur- 70 ing the tablets. I have also constructed the device, as shown in the modification Figs. 3 and 4, having arms attached to a rod or strap D² above and operated at its ends over pulleys by a weight W² and treadle C². The 75 arms F² are hinged or attached to the strap D² and are provided with elastic braces G to cause the arms to move back and forth in the trough A² as the strap D² is moved in one direction by the treadle C² and drawn back by 80 the weight W². The said strap D² passes over pulleys E² E²; but I prefer the construction first above described, as shown in Figs. 1 and 2.

B is one of the tubes which connects with 85 the lower edge of the trough A to receive the pills or tablets. It is made any desired size and shape for receiving the desired tablets or pills. For the ordinary disk tablet the tube is made, as shown in the drawings, with an 90 oval opening. Said tube is provided with a slot or open front B², as shown, so that the operator can see when the tubes are full of tablets or pills. The number of tablets to be counted is determined by the diameter of the 95 tablet and the length of the tube B and the distance between the two contact-points H and L on the lever K, so that by adjusting the length of the lever K the number of tablets can be regulated. Any desired number 100 of tubes may be attached to the lower edge of the trough. I usually use six or more, so that some are always full to be emptied.

The lever K is provided with a suitable fulcrum M, soldered or secured near the tube in 105 any suitable way, and is provided with a rubber band N for holding the lower end or the lower contact-point L down in the tube to prevent the tablets passing down. A spring N² may be used instead of the rubber. 110 I prefer a coil-spring R. When the lever is raised at the lower end, the contact-point H

of the lever at the upper end is so adjusted as to press against one of the tablets Y, and for this purpose the contact-point H of the lever may be made of rubber or other soft material to prevent crushing the tablet or injuring it while being held in place to allow the others below to drop out. I prefer a spring H². When the lower end of the lever is released, the contact-point L, or the lower end of the lever, is drawn back into the tube B by the rubber band N or spring R, or both may be used, and before the tablets released at the upper contact-point H drop past the lower contact-point they are stopped and again fill the tube B between the two contact-points L and H. The lower end K² of the lever is again raised, placing the contact-point H again against one of the tablets and permitting those which are resting on the lower contact-point L to drop out as the lower point L is withdrawn from the tube. By means of the open front of the tube the operator can always tell that the proper number of tablets are in the tube between the two contact-points before he releases them. The operator can always see that the tablets drop out before releasing the lever.

In Fig. 3 a lever K⁴ is shown placed to one side of the tube with two spring contact-points H⁴ and L⁴. A spring R² is used for releasing the upper contact-point when the lever K is released. I have used other means, as a rubber band N and a spring N²; but I prefer the former. Instead of having the contact-points directly beneath the lever the lever can stand to one side of the tube, and the contact may be bent or set on one side of the tube, as shown in the left-hand tube of Fig. 1, so as to expose more conveniently to view the tablets in the tube, or the lever may work with contact-points through the side of the tube, as shown in Fig. 3.

T represents an ordinary slide box or receptacle which is desired to be filled with the tablets or pills.

The trough A may be secured to any desired framework A², and to the said framework or to the tubes are secured stays S and S⁴, which control the length of the stroke of the lever K. To compel contact-points H and L to always enter the slot B², I provide a flaring edge, as shown in Fig. 1, or a sleeve H⁶, as shown in Fig. 5, and a sleeve H⁶ (shown in cross-section, Fig. 5) may be used to prevent the contact-points from entirely leaving the slot or getting out of place. For adjusting the distance of the contact-points H and L they may be secured to a sleeve V to slide on the lever K up and down, as desired, and to hold them in place any suitable means may be used. I prefer a set-screw V². By reason of the slot in the front side of these tubes, which are preferably metal, the operator can see if any tablet sticks or clogs and just where it is and can see that the right

number is always released and drops, and a little jar by the foot or stroke by the operator will usually remove any clog in the tube.

It is operated thus: The tablets or pills, for it will count either pills or tablets, are placed in a trough A and the operator puts a foot in the stirrup C and the foot moves up and down. The strap D moves the lever O in one direction on its fulcrum O³, and the spring W pulls it back when released by the foot. The upper end of the lever O, connecting with the rod P, moves it back and forth, and thus operates the arms F through the tablets and moves them without injury, as they are made of spring material to give easily and covered with rubber to be soft. The trough being triangular or coming together at the bottom, the tablets are turned upon edge and are rolled in this position into the upper ends of the tubes which connect with this bottom edge of the trough. The tubes are thus filled with the tablets on edge, and the diameter being the same they are easily and accurately counted. By regulating the contact-points on the lever K the operator regulates the number of tablets he wants. When the operator raises the lower end of the lever K, this makes the upper contact-point hold one tablet and those above from coming down and releases or opens the lower end and lets all the tablets in the tube between the contact-points drop out. When the lever is released, it is drawn back by the rubber band or spring, and the lower end or contact-point is closed and the upper one is released and the tube above the lower contact-point is again filled, ready to be released again.

Having thus described my invention, what I claim as new, and desire to secure by Letters Patent of the United States, is—

1. In a tablet-counting machine a tube having an opening to receive one tablet at a time upon its edge said tube having an open slot for exhibiting the tablets to view combined with a spring-lever the upper contact-point of which is a spring for stopping and releasing the tablets in the tube without injuring the same.

2. The combination of a triangular trough having tubes connected with its bottom with a stirring mechanism consisting of a rod passing longitudinally through the trough and provided with arms for moving the tablets back and forth in the trough as the rod is moved back and forth substantially as shown and described.

3. In a tablet-counting machine the combination of a triangular trough having oblong tubes connected at its bottom to receive tablets edgewise combined with a stirring mechanism consisting of a rod passing longitudinally through the trough provided with arms for moving the tablets back and forth in the trough combined with a lever for

throwing the rod in one direction and a spring for returning the same substantially as shown and described.

4. In a tablet-counting machine a stirring mechanism consisting of a rod passing longitudinally through the receptacle provided with arms for moving the contents of the receptacle as the rod is moved back and forth combined with a lever one end of which is attached to the foot-piece by a strap and a foot-piece for moving the stirring-rod in one direction and a recoil-spring for moving the same back for stirring the contents of the receptacle substantially as shown and described.

15 5. In a tablet-counting machine a triangular trough and tubes attached to the lower edge of said trough having oblong openings for receiving the tablets upon edge, each of 20 said tubes provided with a spring-lever having two contact-points, the upper one of which is a spring to prevent injuring the tablets when they are being counted, substantially as shown and described.

25 6. In a tablet-counting machine the com-

bination of a tube open the whole length of one side to exhibit its contents combined with a lever having two contact-points said lever provided with a spring for closing its lower contact-point when released by the operator, the upper end provided with a soft contact-point and a stay to prevent the lever from being thrown out too far by the operator when releasing the tablets.

7. In a tablet-counting machine a tube 35 having an open front to exhibit its contents combined with a lever having a spring for drawing its lower contact-point into the tube when released by the operator, the upper contact-point being provided with a spring 40 to prevent injury to the tablets when coming in contact with the same substantially as shown and described.

In testimony whereof I affix my signature in presence of two subscribing witnesses.

SEWARD A. HASELTINE.
